UNITED STATES PATENT OFFICE.

STURGLE DEVARY, OF ESTHERVILLE, IOWA.

FUEL-SUPPLY MEANS FOR INTERNAL-COMBUSTION ENGINES.

Application filed April 23, 1926. Serial No. 104,082.

My present invention has to do with the fuel supply of internal combustion engines; and it contemplates the provision of means adapted to enable an internal combustion engine to develop considerable power and speed with small consumption of gasoline, and this in such manner that but little carbon will be present in the engine.

Other objects and practical advantages of the invention will be fully understood from the following description and claims when the same are read in connection with the drawings, accompanying and forming part of this specification, in which:

15 Figure 1 is a side elevation showing my improvement properly arranged relative to an internal combustion engine.

20 Figure 2 is an enlarged vertical section of the liquid container of my improvement.

25 Figure 3 is an enlarged view taken at right angles to Figure 1, and showing the forward screens of my improvement.

Figure 4 is a detail enlarged longitudinal section showing one of the non-return valves 25 in the conduits intermediate of the liquid container and the mounting in which said forward screens are arranged.

30 Similar numerals of reference designate corresponding parts in all the views of the drawings.

In Figure 1 I show a conventional internal combustion engine 1 having an exhaust conduit 2, and in close proximity to the exhaust conduit 2 and in close proximity to the said exhaust conduit 2 I show a hot plate 3 of conventional or any other appropriate construction designed to receive atmospheric air so that such air will be heated by the heat given off by the said exhaust conduit 2.

40 I also show in Figures 1 and 2 the liquid container 4 of my improvement, the said container 4 being provided with a pendent normally closed drain 5 and having in its interior a baffle plate 6 and a screen 7, the latter being preferably of basket form and being fabricated by preference, of appropriate reticulated material. Leading from the hot plate or analogous device 3 to the container 4 is a conduit 8, the eduction orifice of the conduit 8 being disposed below the said baffle plate 6 as shown in Figure 2. The container 4 is adapted to hold in its lower portion a body of water or other appropriate liquid, water being preferably employed except in extremely cold weather,

at which time an appropriate oil may be used in the container 4 in lieu of water. At 9 the container 4 is provided with a normally closed filling conduit, Figure 1.

The scheme of my invention contemplates 60 the carrying of heated atmospheric air through the conduit 8 and into the container 4 where such air will be caused to pass over and in intimate contact with the body of water or other liquid in the container 4 with 65 the result that such heated air will be saturated with moisture. Communicating with the interior of the screen 7 in the container 4 is a conduit 10, the receiving end of which is closed by an auxiliary screen 11 of reticulated material, the said screen 11 being preferably of general cone shape and being disposed in the comparatively large screen 7. From this it follows that en route between the interior of the container 4 and the conduit 10, the saturated air must of necessity pass first through the screen 7 and then through the auxiliary screen 11, it being noted in this connection that the interstices of the screen 11 are smaller than those of 70 the screen 7 in about the proportions shown in Figure 2, so as to lessen the liability of any impurities reaching the conduit 10 and being carried thereby to the carburetor 12 which is preferably of conventional type, or 75 80 85 of any other construction compatible with the purpose of my invention.

At the opposite end of the carburetor 12, with reference to the conduit 10, is a manifold 13 designed to conduct hydro-carbon 90 fuel to the engine, and interposed between the manifold 13 and the adjacent end of the carburetor 12 is a mounting 14, appropriately connected and equipped with two screens 15 in spaced relation, the said screens 95 15 being preferably of reticulated material as appears in Figure 3.

Connected at their rear ends with the interior of the container 4 and at their forward ends with the interior of the mounting 100 14 at points between the screen 15 are conduits 16, said conduits 16 being preferably arranged at opposite sides of the basket screen 7 in the container 4, and being provided at intermediate points in their lengths 105 with casing enlargements 17, Figures 1 and 4, the said enlargement 17 serving to contain non-return valves 18 and the springs 19 and abutments 20 complementary thereto; and in this connection it will be noted that 110

the non-return valves 18 are arranged to seat toward the rear so as to permit the passage of saturated air forwardly through the conduit 16 while precluding the passage 5 of anything rearwardly through the said conduit 16.

At 19 in Figure 1 I show the internal combustion engine as equipped with a breather device having a foraminous cap 10, and intermediate of the said breather device 19, and the conduit 8 I interpose a conduit 21, the function of which is to conduct heated air from the crank case of the engine to the conduit 8 at a point adjacent 15 to the mentioned hot plate 3.

In the practical use of my improvement, heated air will be supplied through the conduit 8 to the interior of the container 4 and in passing through said container 4, the said 20 air will be saturated with moisture and will be cleared of impurities and supplied through the conduit 10 in a clear state to the carburetor 12, and after being commingled with gasoline in the carburetor 12, such air 25 forming with the gasoline a rich fuel mixture, will pass through the screen 15 and the manifold 13 to the engine, and as the engine increases in speed, the suction created will be sufficient to overcome the action of the 30 springs 19 and unseat the valves 18 so that an auxiliary supply of heated and perforated air will be commingled with the fuel mixture at a point intermediate of the carburetor 12 and the engine, with the result 35 that the engine will be enabled to develop greater power, and at the same time the likelihood of carbon gathering in the engine will be reduced to a minimum.

Manifestly inasmuch as my improvement 40 assures the supply of heated and moistened air to the engine together with the fuel, less fuel will be necessary for the adequate operation of the engine, so that when my improvements are incorporated in an automobile, the automobile may be driven for a 45 considerable distance with the consumption of a small portion of gasoline.

It will be apparent from the foregoing, not 50 notwithstanding the capacity of function ascribed to my improvement, the improvement is simple and inexpensive in construction, is reliable in operation, is well adapted to withstand the usage to which automobile appurtenances are ordinarily subjected, 55 and is susceptible for ready installation in automobiles such as at present in use.

I have specifically described the construction and relative arrangement of parts embraced in the present embodiment of my invention in order to impart a full, clear, and exact understanding of the said embodiment. I do not desire however to be understood as 60 limiting myself to the construction and arrangement illustrated and described, my invention being defined by my present claims

within the scope of which modifications may be made without departure from my invention.

Having thus described the invention, what I claim as new and desire to secure by Letters Patent is:—

1. In combination, an internal combustion engine having an exhaust conduit and also having an intake manifold, a liquid container having in its interior a baffle and also 75 having screen means disposed at one side of the baffle, the portion of the container at the opposite side of the baffle to the said screen means being adapted to hold liquid, a conduit connected to the liquid side of the 80 baffle in the container and adapted to lead heated air to the container, a carburetor, a conduit intermediate of the interior of the screen means in the liquid container and the carburetor, a mounting interposed between the carburetor and the intake manifold, spaced screens in said mounting, and conduit means interposed between the interior of the liquid container and the space 85 between the screen in said mounting and containing non-return means arranged to seat in a direction away from the intake manifold.

2. In combination, an internal combustion engine having an exhaust conduit and also having an intake manifold, a liquid container having in its interior a baffle and also 95 having screen means disposed at one side of the baffle, the portion of the container at the opposite side of the baffle to the said screen means being adapted to hold liquid, a conduit connected to the liquid side of the baffle in the container and adapted to lead heated air to the container, a carburetor, a conduit intermediate of the interior of the screen means in the liquid container and the carburetor, a mounting interposed between the carburetor and the intake manifold, spaced screens in said mounting, conduit 100 means interposed between the interior of the liquid container and the space between the screen in said mounting and containing non-return means arranged to seat in a direction away from the intake manifold; the said screen means in the liquid container being made up of a basket screen of 105 reticulated material, and a smaller screen in the basket screen and over the receiving end of the conduit leading to the carburetor, and having interstices smaller than those of the 110 basket screen.

3. In combination, an internal combustion engine having an exhaust conduit and also having an intake manifold, a liquid container having in its interior a baffle and also 115 having screen means disposed at one side of the baffle, the portion of the container at the opposite side of the baffle to the said screen means being adapted to hold liquid, a conduit connected to the liquid side of the 120 basket screen and over the receiving end of the conduit leading to the carburetor, and having interstices smaller than those of the 125 basket screen.

- baffle in the container and adapted to lead heated air to the container, a carburetor, a conduit intermediate of the interior of the screen means in the liquid container and the carburetor, a mounting interposed between the carburetor and the intake manifold, spaced screens in said mounting, conduit means interposed between the interior of the liquid container and the space between the screen in said mounting and containing non-return means arranged to seat in a direction away from the intake manifold; the said conduit means between the interior of the liquid container and the space between the screens in the said mounting being in the form of pipes with intermediate enlarged casings, and the non-return means being in the form of spring pressed valves disposed in said casing.
- 20 4. In combination, an internal combustion engine having an exhaust conduit and also having an intake manifold, a liquid container having in its interior a baffle and also having screen means disposed at one side of the baffle, the portion of the container at 25 the opposite side of the baffle to the said screen means being adapted to hold liquid, a conduit connected to the liquid side of the baffle in the container and adapted to lead heated air to the container, a carburetor, 30 a conduit intermediate of the interior of the screen means in the liquid container and the carburetor, a mounting interposed between the carburetor and the intake manifold, spaced screens in said mounting, conduit means interposed between the interior of the liquid container and the space between the screens in said mounting and containing non-return means arranged to seat in a direction 35 away from the intake manifold; the said engine being equipped with a breather device, and a conduit being interposed between said breather device and the said conduit for leading heated air to the liquid container.

In testimony whereof I affix my signature.

STURGLE DEVARY.
